UNITED STATES PATENT OFFICE.

ERNEST E. WANGELIN, OF BELLEVILLE, ILLINOIS, ASSIGNOR TO TWENTIETH
CENTURY BRASS WORKS, OF BELLEVILLE, ILLINOIS, A CORPORATION OF
ILLINOIS.

DRINKING-FAUCET.

1,347,566.

Specification of Letters Patent.

Patented July 27, 1920.

Application filed August 29, 1919. Serial No. 320,642.

To all whom it may concern:

Be it known that I, ERNEST E. WANGELIN, a citizen of the United States, residing at Belleville, in the county of St. Clair and State of Illinois, have invented certain new and useful Improvements in Drinking-Faucets, of which the following is a full, clear, and exact description, reference being had to the accompanying drawings, forming a part hereof.

The present invention is directed to improvements in drinking faucets commonly known as bubbling cups, and particularly to that type in which the stream issues from the cup at an incline to prevent any portion of the water intercepted by the mouth of the drinker from dropping back on the cup. One of the objects sought by the present improvement is to provide the faucet with a suitable hood or equivalent formation which will compel the drinker to so position his mouth as to keep the lips from actual contact with the faucet when drinking. A further object is to provide the faucet with suitable means for regulating the force and size of the stream furnishing the water to be drunk, such means being out of reach of persons disposed to tamper with the regulating device. A further object is to construct a faucet or bubbling cup which will be highly serviceable, hygienic, and attractive, and presenting a neat appearance, and one possessing further and other advantages better apparent from the following detailed description in connection with the accompanying drawings in which—

Figure 1 represents a side elevation of the faucet; Fig. 2 is a front elevation; Fig. 3 is a vertical section in the plane of the discharge passage-way taken on the line 3—3 of Fig. 2; Fig. 4 is a top plan of the faucet; Fig. 5 is a horizontal cross-section on the line 5—5 of Fig. 3; Fig. 6 is a horizontal cross-section on the line 6—6 of Fig. 3 with parts broken away; and Fig. 7 is a side elevation of the faucet on a smaller scale showing the same in actual operation.

Referring to the drawings, 1 represents a cup formed with a flaring base 2, the latter being provided with an outer enlarged screw socket *a* for attaching the cup to a suitable water supply pipe *P*, and an inner reduced screw-threaded bore *b* in which operates the tubular screw stem or regulator valve 3,

one end of which is closed by a head 3' provided with a transverse groove *n* for applying a screw driver thereto. The tube 3 is provided with a plurality of peripheral openings or ports *o* adjacent the inner face of the head 3' which serve to establish communication between the source of water supply (pipe *P*) and the chamber of the cup 1. It is clearly apparent from the drawings that the quantity of water admitted into the cup can be regulated by adjusting the position of the openings *o* across the plane of the bottom of the chamber of the cup, a full exposure of the openings above said bottom admitting a maximum quantity of water and a partial exposure a less quantity; and if the valve 3 be screwed toward the socket *a* sufficiently to entirely close the ports *o* by the walls of the bore *b*, the water will be entirely cut off. Of course the ports *o* are disposed in a common plane transverse to the axis of the regulator tube 3, so that the several ports are all affected alike with any movement imposed on the regulator.

The top of the cup 1 is closed by a screw cap or lid 4 which, when fully driven home, shoulders against the edge of the cup, the top of the screw-cap being more or less dome-shaped as shown. The said screw-cap is perforated by an inclined passage-way *h* cutting across the common axis of the cap and cup whereby the same discharges the water from the cup to one side of said axis. Formed with the screw-cap 4 and projecting above the same, and contoured to protect the top and sides of the water stream *S* issuing from the passage-way *h*, is a hood or cowl 5, the same being spaced from the stream on all sides as clearly obvious from the drawings (Figs. 2, 3). The hood is substantially U-shaped in cross-section and practically envelops the screw-cap 4 circumferentially over an arc of substantially one hundred and eighty (180) degrees or more, thereby preventing approach to the bottom portions of the stream *S* from the rear or sides. The side walls of the hood are disposed symmetrically on opposite sides of the passage-way *h* and the water stream *S* issuing therefrom. The hood as a whole is so shaped as to prevent the application of the lips of the drinker to the outer surface of the screw-cap 4. The hood may be said to terminate

at the top in a reduced extension 5' which, as clearly shown in Fig. 7, prevents the lips L of the drinker from being applied to the top of the lower portion of the stream S, 5 the shortest distance between the stream and the lips when resting against the extension 5' being too great to permit the lips to reach the stream, (dotted position Fig. 7). The consequence is that since the stream can 10 not be approached or engaged by the lips from the sides or rear; and since the hood extension 5' arrests the lips before they can be applied to the lower portion of the stream from the top, the drinker will be forced to 15 attack the stream at some point in front of the hood away from the cup, say substantially at a point designated by α in Fig. 7. At this point the lips of the drinker will be entirely out of contact with any portion 20 of the bubbler or faucet, the overflow from the mouth falling out of range of the cup, thereby making the cup perfectly hygienic.

It will be seen from the drawings that the lid or screw-cap 4 has considerable thickness 25 thereby imparting to the passage-way h considerable length, the passage-way thus elongated operating to give the stream definite direction without material spreading while traversing the space bounded by the hood, 30 so that a coherent stream is directed into the mouth. The intensity of the stream is of course regulated by the valve 3 which determines the rate of influx of the water into the cup 1 as above described. The said 35 valve is out of reach of mischievous persons, being protected by the lid 4 which after being driven home is secured to the cup walls by a set screw 6 driven flush with the outer face of the cup. The latter is provided with the usual relief port o' which causes the water to be forced downward in 40 the event some one should close the discharge end of the passage-way h as well understood in the art, this port being too 45 small to allow any material quantity of water to leak out under normal operating conditions. The faucet may obviously be changed in many details without involving a departure from the nature or spirit of the

invention. In the present embodiment of the 50 invention the extension 5' is in the general direction of the longitudinal axis of the cup and lid, and to one side of said axis, but I wish to be understood that I am not to be restricted to this precise position, nor to the 55 specific shape of hood as shown.

Having described my invention what I claim is:

1. A drinking faucet comprising a cup 60 communicating at one end with a suitable source of water supply, a screw-cap or lid closing the top of the cup, said lid being formed with an elongated open ended passage-way communicating respectively with the interior and outside of the cup, said passage-way being disposed across the axis of the cup and lid, a regulator valve interposed between the water supply source and chamber of the cup, and a hood or cowl 65 leading from the outer boundaries of the lid and extending circumferentially partially around the lid to envelop the sides and top portions of the bottom of the stream issuing from the passage-way, the hood terminating at the top in a reduced portion extended in the line of the axis of the cup to a point to intercept the lips of the drinker approaching the stream from the top, the sides of the hood preventing 70 approach of the stream from the sides. 75

2. In a drinking faucet of the character described and discharging a stream at an incline to the vertical, a hood encompassing the sides and top of the bottom of the stream so discharged to prevent approach to the 80 stream from three directions, and a reduced extension leading from the hood upwardly to a point sufficient to prevent the lips when resting on the extension from engaging the stream, said extension being in the general 85 direction of the vertical axis of the faucet and to one side of the same. 90

In testimony whereof I affix my signature in presence of two witnesses.

ERNEST E. WANGELIN.
